RAILWAY CAR TRUCK

William A. Geiger, Chicago, Ill., assignor to
 William P. Sidley, M. F. Back, Albert P.
 Withall, Edwin C. Austin, and George A.
 Johnson, all of Chicago, Ill., and Alice T. Miner,
 Chazy, N. Y., as trustees of The William H.
 Miner Foundation

Application July 13, 1944, Serial No. 544,664

7 Claims. (Cl. 105—197)

1

This invention relates to an improved railway car truck, and particularly to an improved bolster snubbing means therefor.

One of the objects of the invention is to provide a snubbing or shock-absorbing means for the bolster which is adaptable to the side frames of the truck without the necessity of materially changing or enlarging the usual frame and bolster.

More specifically, my object is to provide within the confines of the walls of the side frame, snubbing or shock-absorbing means which frictionally acts upon the side walls of the bolster to dampen the vertical movement of the bolster in the frames.

Other objects of the invention will appear from the following description and claims in connection with the accompanying drawing.

Referring to the drawing,

Fig. 1 is a vertical outer face view of the central portion of one side of a railway car truck showing the associated side frame, bolster and spring cluster, and illustrating my improved snubbing means in connection therewith;

Fig. 2 is a horizontal section on the line 2—2 of Fig. 1;

Fig. 3 is a view similar to Fig. 1, illustrating a modified form of snubbing mechanism;

Fig. 4 is a horizontal section on line 4—4 of Fig. 3; and

Fig. 5 is a view similar to Fig. 1, illustrating still another modification of snubbing mechanism.

In the drawing, A indicates one of the side frame members of a railway car truck. As will be understood by those skilled in the art, a railway car truck includes two side frame members A, a transverse truck bolster B, a spring seat C' in the lower portion of each frame, and a spring cluster C supporting each end of the bolster for vertical movement.

The usual side frame has a central opening D therein, the lower portion of which is wide enough to admit the bolster endwise for assembly and disassembly of the parts, and the upper portion of which is narrowed to the width of the bolster to guide the bolster in its movement.

The usual side frame is in the form of a casting which in general comprises two vertical side walls 11 spaced apart in parallel relation and joined by top and bottom walls 12 and 13 respectively. Openings 14 are generally provided in the side walls, which communicate with the space between the walls for access to the interior of the

frame and for other purposes not directly concerned with this invention.

The bolster opening D is bounded at the top by a top wall 15 and at the bottom by the spring seat C', and at its sides or ends by the vertical walls 16, except at the upper narrower portions which are left open in accordance with my invention for the snubbing mechanism, these walls all being integral with and connecting the two side walls of the frame.

The end of the bolster is positioned between the end margins of the upper portion of the opening and is guided thereby for vertical movement in the frame. The bolster is provided with guide lugs 17 which embrace the outside of the side walls of the frame to prevent endwise movement of the bolster. The lower portion of the opening is wider so that in assembling, the bolster can be inserted endwise into the opening and then raised up into position. This portion of the opening also provides space for the bolster supporting springs C. As is well known in the art, the springs C are generally in the form of coil springs, a plurality of which are arranged in a nest or cluster and positioned between the bolster and the spring seat C', thus providing a yielding support for the bolster.

The bolster end portions are generally rectangular in section and are formed as hollow castings having horizontal top and bottom walls 18 and vertical side walls 19 which lie adjacent the margins of the bolster openings and which, in accordance with my invention, provide friction faces upon which the snubbing mechanism acts.

In the structure shown in Figs. 1 and 2, the friction shoes or members are in the form of bell cranks or L-shaped levers with plates 20 and 21 disposed at right angles and joined by webs 22 through which the pivot bolts 23 extend to form fulcrums for the levers. The levers are positioned between the side walls of the frame in the upper portion thereof, and the pivot bolts are supported by these side walls.

The friction shoes or plates 21 are substantially parallel with the bolster end walls 19, and are maintained in frictional engagement with the bolster side walls by springs 24. These springs 24 are seated upon the horizontal plates 20 of the bell cranks and are placed under compression between these plates 20 and the top wall 12 of the side frame and thus act to swing the bell cranks about their fulcrums and force the friction shoes 21 against the bolster end walls 19. While the spring means may be of any suitable form for the purpose, I prefer coil springs for this purpose.

Centering lugs 25 are provided on the horizontal plate members 20 and on the inner face of the top wall 2 of the frame to hold the springs in place.

In the structures shown in Figs. 3 and 4, the bell cranks are somewhat in the form of ice tongs fulcrumed upon a common pivot bolt 27 and mounted in the frame above the center of the bolster. In this form, the spring pressed arms 28 of the bell cranks extend horizontally in opposite directions and are positioned above the bolster and the springs 24 are positioned under compression between these arms 28 and fixed seats 29 formed on the inner faces of the frame side walls and extending crosswise thereof.

The friction shoe members 30 are disposed vertically in substantially parallel relation to the bolster end faces to frictionally engage said end faces, but friction shoe members associated with each arm 28 are disposed on the opposite side of the bolster to that of its arm. Each shoe member is carried by the diagonally extended arm 31 which is joined to the corresponding arm 28 and mounted upon the fulcrum bolt 27. As shown more particularly in Fig. 4, one of the levers consisting of the arm 28 and the arm 31 is provided with an opening 32 through which the arm 28 of the other lever extends, so that the arms 28 of the levers are disposed on the opposite side of the bolster to the friction shoes which they carry. Thus in this form of the invention the upward pressure of the springs on the arms 28 swings the shoes into frictional engagement with the bolster. In this structure, the top wall 15 of the bolster opening is omitted to provide operating space for the arms 31 of the levers.

In the structure shown in Fig. 5, the levers are similar to those of Fig. 1, except that the spring-pressed arms 42 of the levers are disposed vertically in line with the frictional members or shoes 21. These are extended upwardly into the portion of the side frame above the top wall 15 of the bolster opening in position to form seats for the coil springs 33 which are positioned under compression between these seats and a central transverse web 34 in the side frame. Thus the springs acting outwardly against the arms 42 swing the levers about their fulcrum bolts 23 and force the shoe members 21 into frictional engagement with the bolster walls. If desired, the action of the springs 33 can be supplemented by additional springs 35. These springs, however, instead of being under compression, are under tension and are anchored at their outer ends by the bolts 36 and with their inner ends connected by means of the lugs 37 on the lever arms 42. Thus these springs act to pull upon the arms 42 of the levers and thus their effect is cumulative with respect to the springs 33.

Thus self-contained snubbing mechanism is provided entirely within the confines of the side frames. The friction shoes bear upon the end walls of the bolster and thus serve as snubbers by developing a frictional resistance to the main springs C and thus dampen the compression and recoil or rebound of said main springs to minimize the vibration imparted to the car body.

I claim:

1. In a railway car truck, the combination of a side frame having an opening therein, a bolster disposed transversely of the truck and guided for vertical movement in said opening, spring means in the frame below the bolster for supporting

said bolster, pivotally mounted friction shoes in said frame positioned adjacent the side walls of the bolster, and having arm extensions above the bolster and spring mechanism independent of said bolster supporting spring means positioned between the arm extensions and the frame above the bolster acting on said arm extensions to force the shoes into frictional engagement with the bolster to snub the movement of said bolster.

2. In a railway car truck, the combination of a side frame comprising side walls spaced apart and having a bolster opening therethrough, a bolster disposed transversely of the truck and guided for vertical movement by the wall margins of said opening, spring means below the bolster supporting said bolster in said frame, pivotally mounted levers positioned between the walls of the frame and having friction shoe portions frictionally engaging the side walls of the bolster, said levers having arms forming spring seats, and springs in the upper part of the frame above the bolster compressed between said spring seats and the frame for forcing the shoe portions against the bolster.

3. In a railway car truck, the combination of a side frame comprising side walls spaced apart and having a bolster opening therethrough, a bolster disposed transversely of the truck and guided for vertical movement by the wall margins of said opening, spring means below the bolster supporting said bolster in said frame, a lever pivotally mounted between the walls of the frame adjacent each side of the bolster and having a friction plate frictionally engaging a vertical side face of said bolster, arms for said levers providing spring seats, and coil springs independent of said bolster supporting spring means positioned within the frame above the bolster and compressed between said spring seats and the frame for yieldingly forcing said friction plates against the bolster to snub the movement of the bolster.

4. In a railway car truck, the combination of a side frame comprising side walls spaced apart and having a bolster opening therethrough, a bolster disposed transversely of the truck and guided for vertical movement by the wall margins of said opening, spring means supporting said bolster in said frame, vertically disposed friction plates pivotally mounted between the walls of the frame adjacent the sides of the bolster, lateral horizontally disposed extensions on said plates, and vertically disposed coil springs within the frame above said bolster and compressed between said lateral extensions and the frame for forcing the friction plates into frictional engagement with the vertical faces of the bolster to resist the compression and rebound of said bolster supporting spring means.

5. In a railway car truck, the combination of a side frame comprising side walls spaced apart and having a bolster opening therethrough, a bolster disposed transversely of the truck and guided for vertical movement by the wall margins of said opening, spring means supporting said bolster in said frame, vertically disposed friction plates pivotally mounted between the walls of the frame adjacent the sides of the bolster, vertical extensions on said plates above the pivots thereof, and horizontally disposed coil springs within the frame above the bolster opening and compressed between said extensions and a seat in the frame for forcing the friction plates into frictional engagement with the vertical side

faces of the bolster to resist the compression and rebound of the bolster supporting spring means.

6. In a railway car truck, the combination of a side frame comprising side walls spaced apart and having a bolster opening therethrough, a bolster disposed transversely of the truck and guided for vertical movement by the wall margins of said opening, spring means supporting said bolster in said frame, vertically disposed friction plates pivotally mounted between the walls of the frame adjacent the sides of the bolster, vertical extensions on said plates above the pivots thereof, horizontally disposed coil springs within the frame above the bolster opening and compressed between said extensions and a seat in the frame, and supplemental coil springs under tension and connected to the extensions and the frame and acting cumulatively with said compressed coil springs for forcing the friction plates into frictional engagement with the bolster faces to frictionally resist the compression and rebound of said bolster supporting spring means.

7. In a railway car truck, the combination of a side frame comprising side walls spaced apart and having a bolster opening therethrough, a bolster disposed transversely of the truck and guided for vertical movement by the wall margins of said opening, spring means supporting said bolster in said frame, levers positioned between the walls of the frame above the bolster opening and pivotally mounted upon a common fulcrum, said levers being disposed horizontally and extending in opposite directions beyond the width of the bolster, and each lever having an arm extending to the opposite side of the bolster, a friction shoe plate on each arm adapted to be swung into frictional engagement with the adjacent side wall of the bolster, and coil springs vertically disposed in the frame and compressed between seats in the frame and the horizontally extended levers for swinging said friction plates against the bolster.

WILLIAM A. GEIGER.
